SPRING BASE FOR SEATS

Richard A. Nowell, Los Angeles, Calif., assignor to
 Metal Products, Inc., doing business as Metal-
 craft Products Co., a corporation of California

Application June 27, 1949, Serial No. 101,660

2 Claims. (Cl. 155—179)

1

This invention relates to a spring base for the seats of chairs, sofas, and other articles of furniture which afford cushioned seating or reclining accommodations, particularly upholstered furniture.

One of the objects of this invention is to provide as a hardware unit for furniture of the character described, a preformed spring support or base which may be installed with appreciable saving in time, labor and costs as compared to spring seat arrangements heretofore employed, and, additionally will prove superior to such previous spring arrangements in point of simplicity of construction, compactness, taking up less space, providing better ventilation, providing for an easier application of the upholstery to complete the seat, and increasing the cushioning action and seating comfort.

Another object of this invention is to provide a spring base unit such as described in which a metal frame supporting a plurality of bowed sinuous springs for immediate support of the seat upholstery, is in turn supported by special mounting springs permanently fixed to the frame and adapted to be fastened to the base frame of the chair, sofa or the like, whereby the seat is bodily yieldable as a unit on said mounting springs thereby increasing cushioning action and seating comfort.

Another object is to provide a spring base for seats wherein a novel adjustment of simple construction makes it possible to regulate the spring action of the base best to suit the particular chair, sofa or the like.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a part sectional and part side elevational view showing a spring seat base embodying the present invention and as installed in an arm chair;

Fig. 2 is a fragmentary horizontal sectional view taken on the line 2—2 of Fig. 1, and

Fig. 3 is an enlarged fragmentary sectional view taken on the line 3—3 of Fig. 2.

In accordance with this invention I provide as a hardware unit for seats, a preformed spring seat base which generally includes an angle bar frame 4 here shown of rectilinear form, a plurality of sinuous and upwardly bowed springs 5 extending across and supported by the frame

2

4 and a pair of especially coiled springs 6 fixed to the frame as by being welded thereto and which provide for yieldably supporting the unit in place for example on the base frame or structure 7 of a chair 8 as here shown.

The upwardly bowed sinuous springs 5 are of a well known type widely used in this art and are secured to the opposed frame bars 4a by having their right angularly bent ends 9 extending through sleeve portions 10 on U-shaped clips 11 fitted onto said frame bars.

Each of the mounting springs 6 is made of a single piece of spring wire bent to form opposed coils 12, a straight length 13 of the wire joining the coils in substantially coplanar relation to the upper edges of said coils, and two like crossed end lengths 14 and 15 which extend forwardly and rearwardly from the coils and are adapted to be fastened to the chair frame 7.

20 The upper straight lengths 13 of the springs 6 are fixed to the other opposed frame bars 4b at points approximately centrally of the ends of the latter as by being welded thereto as at 16 as shown in Fig. 1, thereby permanently joining the springs 6 to the frame 4 with the crossed end lengths 14 and 15 extended for being fastened to the chair or other article of furniture to which the base unit hereof may be applied. These end lengths 14 and 15 have right angularly bent ends 17 and 18. The ends 17 of the lengths 14 are extended through clips 19 then into the ends of a tubular connecting member 22 which lends desired rigidity and maintains the proper assembly of the parts associated therewith. The ends 18 of the lengths 15 are extended through adjusting brackets 21 then into the ends of a tubular connecting member 29 corresponding to the tubular member 22. Each of the brackets 21 is provided with upstanding, opposed and slotted ears 23 between which a tubular bearing 23' is mounted. The ends 18 extend through the bearing 23' and are adjustable in the slots of said ears for the purpose to be hereinafter described. The clips 19 and brackets 21 provide for fastening 30 the base unit to the chair or other article of furniture and as here shown the clips 19 are secured to the frame 7 of the chair 8 by means of suitable fastenings 24 whereas the brackets 21 are secured to the frame 7 by means of bolts 35 25 and nuts 26 as best shown in Fig. 3.

It should be noted that the frame 4, with the sinuous springs 5 and the mounting springs 6 fixed thereto constitutes a preformed base of ready and easy applicability to the furniture article in which it is to be installed and may if de-

sired include in assembled relation to the springs 6, the clips 19, brackets 21 and the connecting tubes 20 and 22, thereby providing a more complete hardware unit.

In the use of the spring base unit as here shown in a chair, after it is installed, the chair upholstery designated at A in Fig. 1 and the webbing strips B are applied to the unit in any suitable manner or may be applied to the unit before its application to the chair. A detailed account of how the upholstering or the finishing operation of the seat for which the base hereof is used is thought to be unnecessary as it forms no part of the present invention except that the webbing pieces B at the front and rear of the seat act as snubbers to limit the upward movement and prevent pronounced or undesirable fore and aft rocking of the seat while permitting of bodily depression of the seat as a whole and the full cushioning action of the springs 5 and 6.

In this connection it is seen that the rear piece of webbing B is fastened as at 27 to the rear of the base frame 7 of the chair and as at 28 to the seat whereas the front piece of webbing B is fastened to the front of the seat and to a wooden strip 29 fixed to the frame 4 in any suitable manner. This webbing is extended downwardly from the strip and fastened to the chair frame 7 as at 30. In practice the webbing B may be fastened so as to place the springs 5 and 6 under an initial compression and while it prevents undue rocking of the seat and limits upward movement it permits free bodily depression of the seat relative to the chair frame. However, the amount of slack in the webbing determines the limited rocking action of the seat.

The action of the springs 6 may be varied by fastening the brackets 21 at different points on the frame 7. As shown in the drawing the brackets are secured in place so that the ends 18 of the springs 6 are seated at the rear ends of the slots in the ears 23 and maximum resistance of the springs 6 is provided for. If the brackets 21 are fastened down so that the ends 18 are spaced outwardly from the rear ends of the slots in the ears 23, the ends 18 will slide in the slots before the resistance of the springs 6 comes into play and thus the spring action of the springs 6 may be varied by changing the position of the brackets 21 as desired.

It should be noted that in having the mounting springs 6 fixed intermediate their ends to the undersides of the opposed side bars of the frame 4 at points centrally of the ends of said bars and entirely below the frame 4 a most effective added

cushioning action is afforded by said mounting springs and the installation of the unit is greatly facilitated by reason of the accessibility of the springs 6 and associated parts as a result of this arrangement.

While I have shown and described a specific embodiment of my invention I do not limit myself to the exact details of construction set forth, and the invention embraces such changes, modifications and equivalents of the parts and their formation and arrangement as come within the purview of the appended claims.

I claim:

- 15 1. In a spring base for the seat of a chair, sofa or the like, a frame, a plurality of spring members fixed at their ends to and extending across the frame as a support for the upholstery to be applied to complete the seat, a pair of mounting springs fixed intermediate their ends to the frame and depending therefrom, and means affording the fastening of the ends of said mounting springs to the base structure of the chair, sofa or the like including brackets formed with opposed slotted ears in the slots of which certain ends of said mounting springs are slidable.
- 20 2. A hardware unit for a spring seat comprising a rectangular metal frame, a plurality of upwardly bowed and sinuous spring members fixed at the ends to certain opposed members of said frame, spring devices welded intermediate their ends to the under sides of the other opposed members of the frame at points approximately centrally of the ends of said other opposed members and depending therefrom with their ends extending in opposite directions, and means at said ends of said spring devices affording the fastening of said ends to the base structure of a chair, sofa or the like.
